UNITED STATES PATENT OFFICE.

JOHN B. BANOWETZ, OF DENVER, COLORADO.

SHAVING-BRUSH.

1,087,090.

Specification of Letters Patent.

Patented Feb. 10, 1914.

Application filed March 20, 1913. Serial No. 755,744.

To all whom it may concern:

Be it known that I, JOHN B. BANOWETZ, a citizen of the United States, residing at Denver, in the county of Denver and State of Colorado, have invented certain new and useful Improvements in Shaving-Brushes, of which the following is a specification, reference being had therein to the accompanying drawing.

10 This invention relates to shaving brushes and has special reference to a fountain brush which is adapted to carry the shaving powder, and from which the powder may be distributed in even quantities upon the bristles.

15 The principal object of this invention is the production of a discharge spout which is provided at its lower end with a crimped portion constituting an inwardly extending circumferential flange, the face thereof being engaged by the closure-plunger for preventing dampness from entering into the interior of the casing.

20 A still further object of the invention is the production of a spring housing which is adapted to contain the spring that engages the plunger, whereby the powder will be prevented from packing around the spring and rendering the same less efficient.

25 With these and other objects in view, this invention consists of certain novel combinations, constructions and arrangements of parts as will be hereinafter fully described and claimed.

30 In the accompanying drawing: Figure 1 is a vertical section of the shaving brush. Fig. 2 is a vertical section of the casing. Fig. 3 is a vertical section of the bristle containing body. Fig. 4 is a section taken on the line 4—4 of Fig. 2, looking in direction 35 of the arrow. Fig. 5 is a perspective view of the closure-plunger head. Fig. 6 is a vertical section of a modified form of a plunger head.

35 Referring to the accompanying drawing by numerals, it will be seen that the device comprises a hollow cylindrical casing 1 having at its lower portion the threads 2. This casing 1 is provided at its upper end with a cover 3 which is formed integrally therewith, this cover being provided with a collar 4, the collar 4 being provided with a depending flange 6 having a depending hollow housing 5, the lower end of the housing 5 being provided with a bottom 7 in which there 40 is formed an aperture 8.

The bristle containing-body is provided with a pocket portion 9 which is crowded in upon the bristles 10 from the position illustrated in dotted lines in Figs. 1 and 3. This pocket portion 9 is provided at its upper portion with a circumferential rib 11 which is formed adjacent the threaded portion 12. The threaded portion 12 is provided with an integral bowl 13 having at its lower portion the discharge spout 14, this discharge spout 14 extending below the pocket-portion 9 and is provided at its lower end with a crimped portion constituting an inwardly extending circumferential flange 15. By placing the bristles around the spout 14 and by crimping the pocket-portion 9 upon the bristles, they will be held securely in engagement with the lower portion of the brush. After the bristle containing member has been formed, as described, it is screwed in engagement 45 with the casing 1 by means of the threads 2 and threads 12.

A plunger rod 16 is passed through the housing 5 and the aperture 8, this plunger rod 16 being provided at its lower end with the enlarged head 17 which is adapted to slide within the discharge spout 14 and rest upon the flange 15 for forming a tight closure. By referring to the drawing it will be seen that the head 17 engages the inner face 50 of the crimped portion of the spout forming the flange, the crimped portion or flange constituting a cap structure for the outer end of the plunger head, and in this manner prevent any moisture from entering into the 55 casing 1 and caking the powder. This plunger rod 16 is also provided with a bearing collar 18 which is positioned within the housing 5. A coiled spring 19 is positioned around the plunger rod 16 and within the housing 5 60 and bears at its lower end portion upon the collar 18 for normally holding the head 17 upon the circumferential flange 15 for forming a tight closure for the spout 14. This spring is held within the housing 5 by means 65 of the cap 20 which is provided with the threaded portion 21 which is adapted to engage the flange 6. The upper portion of the plunger rod 16 is provided with a lifting handle 22 whereby the head 17 may be 70 moved from the discharge spout 14 when it is desired to force the powder from the interior of the casing 1.

The plunger head, disclosed in Fig. 6, is used in combination with the above de- 75

scribed brush and is adapted to work within the discharge spout 14. This plunger head is provided with a body portion 23 which engages the lower portion of the plunger rod 16 and is provided at its lower portion with the flared portion 24 which is adapted to engage the side portions of the discharge spout 14 for scraping the powder therefrom and forcing it from the interior 10 of the spout.

When this device is used, the bristle containing member may be removed at which time the powder may be placed within the casing 1. The bristle containing member is 15 then threaded into engagement with the casing 1 at which time the head 17 will rest upon the inner face of the flange 15. The brush will then assume the position, as 20 illustrated in Fig. 1. By grasping the member 22 and lifting the same the spring 19 will be compressed, and the head 17 will be lifted from engagement with the flange 15 out of the discharge spout 14 whereby the powder contained within the casing 1 may 25 pass through the discharge spout 14 and be distributed upon the bristles 10. By releasing the handle 22, the spring will cause the plunger head to be moved down into the discharge spout 14 and drive the powder con- 30 tained therein from the spout. The head 17 finally rests upon the circumferential flange 15 and in this manner forms a tight closure for the discharge spout. The bristles may 35 then be wet without danger of the moisture passing around the lower portion of the discharge spout and entering the casing, as the force of the spring 19 will hold the head firmly in engagement with the inner face of the circumferential flange 15.

40 From the foregoing description, it will be seen that a simple and efficient shaving brush has been produced which will force a quantity of powder upon the bristles and which is provided with a flange portion 45 which will prevent any moisture from entering into the interior of the casing, and in this manner will keep the powder contained within the casing in a suitable condition for easily discharging the same.

50 Having thus described the invention, what is claimed as new, is:—

1. A shaving brush comprising a casing, said casing provided at its lower portion with a discharge spout, said casing also provided with bristles positioned about said discharge spout, said discharge spout provided at its lower portion with an inwardly extending flange, and a closure-plunger positioned within said casing and being adapted to engage the inner face of said flange, thereby closing said spout, whereby moisture will be prevented from entering the casing.

2. A shaving brush comprising a casing, 65 a bristle-containing member carried by the

lower portion of said casing, said containing-member provided with a pocket-portion, bristles carried by said pocket-portion, a rib formed upon said pocket-portion and a plurality of threads formed adjacent to said rib, said rib limiting the inward movement of the bristle-containing-member upon said casing, a bowl-portion formed integral with said threads, a depending discharge-spout formed upon said bowl-portion and depending beyond the lower portion of said pocket-portion, said discharge-spout provided at its lower portion with an inwardly extending flange, and a closure-plunger in said casing and adapted to engage the inner face of said flange for tightly closing said discharge-spout, whereby moisture will be prevented from entering said casing.

3. A shaving brush comprising a casing, a discharge spout carried by the lower portion of said casing, said casing provided with an integral depending housing upon its inner portion, a plunger rod slidably mounted within said casing and passing through said housing, said plunger rod provided with a head adapted to close said discharge spout, said plunger rod provided with a collar, a spring positioned within said housing and bearing upon said collar for holding said head in a closed position, a cap engaging the upper portion of said housing for holding said spring within said housing, means for raising said plunger head, and said housing constituting a means for preventing powder from becoming caked about said spring and rendering the same less efficient.

4. A shaving brush of the class described comprising a casing, said casing provided with an opening at its lower end, an integral sheet metal cover on the upper end of said casing, said cover provided with an integrally formed downwardly extending flange upon its lower side forming a housing, a plunger carried within said casing and adapted to close said opening, a spring on said plunger, within said housing, whereby the powder carried within said casing is prevented from packing around the spring rendering the spring less effective for holding the plunger in the closed position, and a closure for said housing forming an abutment for said spring.

5. A receptacle provided with a discharge opening at one end, a head at the opposite end of said receptacle, a housing extending into said receptacle from said head, a plunger extending through said receptacle and through said housing, a head at the inner end of said plunger, and resilient means in 120 said housing engaging said plunger for normally holding the head of said plunger in a position to close the discharge opening of said receptacle.

6. A receptacle, a discharge spout extend-

ing from one end of said receptacle, a plunger extending into said receptacle, and a hollow head carried by the inner end portion of said plunger and extending into said spout and provided with a flared tapered end portion engaging the walls of said discharge spout whereby any of the contents of said receptacle which may adhere to the

walls of said discharge spout may be scraped off.

In testimony whereof I hereunto affix my signature in presence of two witnesses.

JOHN B. BANOWETZ.
